(57) **CLAIM**

The ornamental design for a stand mixer, as shown and described.

DESCRIPTION

FIG. 1 is a front perspective view showing a stand mixer according to a first embodiment of our new ornamental design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view showing a stand mixer according to a second embodiment of our new ornamental design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front perspective view showing a stand mixer according to a third embodiment of our new ornamental design;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

Applicants specifically reserve the right to pursue portions of each of the designs disclosed herein, e.g., various portions of each stand mixer (such as any individual component in isolation, e.g., the frame/stand or veneer thereof, bowl, lid, etc.), various portions of the components thereof and/or combinations of or the interface between components or portions thereof.

The broken lines represent environment or structure of the stand mixer and do not form any part of the claimed design.

The stippling in FIGS. 8-21 indicates contrast.
